Application December 17, 1946, Serial No. 716,767

10 Claims. (Cl. 24—263)

1

This invention relates to oil well drilling equipment and particularly pertains to an automatic drill slip unit.

In oil well drilling operations it is common practice to temporarily grip a suspended string of pipe by introducing slips into the bowl of a rotary table and around the string of pipe so that the slips will wedge between the tapered wall of the bowl and the cylindrical surface of the pipe to hold the pipe. The simplest form of slip structure is a member which is arcuate in section having an inner arcuate face conforming substantially to the circumference of the pipe to be gripped and which face is preferably wickered to insure positive gripping action. The outer arcuate face of the slip is tapered so that it will conform to a segment of the circumference of the tapered bowl. Three or more such slips are used as a set and due to their individual weight handles are normally applied to them so that one or two men can lift the slip to place it in position within the bowl and to remove it therefrom. This operation is laborious and objectionable since the slips and the surface of the rotary table are often covered with drilling mud and oil. Various attempts have been made to produce a structure carrying a set of slips and acting to set the slips simultaneously within the bowl or to withdraw them therefrom. In view of the fact that the slips weigh considerable and that they must be arranged to encompass the suspended pipe the supporting members for the slips have been complicated in construction and have also required the use of complicated and expensive power lifting means. It is desirable to provide a slip structure which will carry a plurality of slip elements and will allow them to be easily mounted in position or removed therefrom by a simple manual operation, and it is the principal object of the present invention, therefore, to provide a portable base structure adapted to be positioned near a rotary table on the derrick floor when required, and which structure carries a hanger for supporting a set of slips and being manually operable to move the slips to a set position and to withdraw them therefrom with ease.

In order that a device of the present character may serve effectively its intended function of positioning the slip elements within a rotary table, it is desirable that the slips be so carried by their supporting structure as to be rotatable relative to that structure about the axis of the table. To provide for such rotation it has heretofore been considered necessary that the supporting structure include at least one member or ring extend-

2

ing entirely about the pipe in use and thus requiring partial disassembly upon movement into and out of an active position about the drill pipe. The resulting inconvenience in handling such slip units has caused most oil workers in practice to avoid the use of any mechanical unit of the present type and to position the slips entirely by hand.

A particular object of the present invention is to provide a slip supporting structure so formed as to effectively guide the slips for rotation while not requiring even partial disassembly upon movement into and out of active position. Specifically, I prefer to employ as supporting elements a pair of members or rings adapted to extend about a drill pipe, and rotatably interconnected so that one acts as a support by which the other, carrying the slips, is rotatably mounted. To permit movement of the unit into and out of active position without the necessity for disassembly, I form the two relatively rotatable rings to have registrable openings or pipe passing throats in their sides, and I interconnect the rings in a novel manner guiding them for relative rotation without the necessity for any bearing engagement at the throat locations. As will appear, a critically important feature in providing for such rotary support is the employment of unique bearing means particularly characterized by a capacity for affording bearing engagement between the rings at at least five different locations spaced angularly about the rings. As a result of this capacity for five point bearing engagement, I assure that even when the rings are not in engagement at one of the five bearing locations, by reason of the movement of one of the open throats to that location, there is still an effective four point engagement between the rings.

The present invention contemplates the provision of a base structure carrying a standard upon which a walking beam is pivoted, one end of said beam carrying a counterweight and the other end of the beam carrying a slip ring from which a plurality of slips are suspended by articulate connections.

The invention is illustrated by way of example in the accompanying drawing in which:

Figure 1 is a view in plan showing the automatic slip unit with which the present invention is concerned.

Fig. 2 is a view in side elevation showing the automatic slip unit with its parts in their set position and indicating by dotted lines the position of the parts when in retracted position.

Fig. 3 is a view in transverse vertical section as seen on the line 3—3 of Fig. 1 and shows the composite slip supporting ring.

Fig. 4 is a fragmentary view in side elevation as seen on the line 4—4 of Fig. 2 and shows the latch lever.

Referring more particularly to the drawing, 10 indicates a base plate upon which is mounted a vertically disposed cylindrical standard 11. This standard carries bearing rings 12 and 13 near its upper and lower ends. Telescoping over the standard 11 is a vertical column 14 which is tubular and has an inner bore of a diameter to provide a running fit with the bearing rings 12 and 13. The column rests at its lower end upon a thrust ring 15 which circumscribes the standard and rests upon the bearing plate 10. Mounted upon the outer face of the column at a point in the length of the area circumscribed by the standard 11 is a pair of lugs 16 carrying a pivot pin 17. The pivot pin 17 extends horizontally and provides a support for a latch lever 18. One end of the latch lever is formed with a handle 19 and the opposite end is formed with a latch dog 20. The latch dog 20 may extend through an opening 21 in the wall of the column 14 and into an opening 22 in the wall of the standard 11. When the latch dog extends into both of said openings the column 14 will be held against axial rotation with relation to the standard 11 and will prevent the column from being lifted clear of the standard. The upper end of the standard 11 is fitted with a handle or bail 23 by which the column and the structure therewith may be lifted from the standard when desired. A horizontally extending king pin 24 passes through the column 14 near its upper end as accommodated by diametrically opposite openings 25 formed through the walls of the column. The king pin is provided as a pivotal connection for a walking beam 27. The walking beam 27 extends oppositely from the king pin 24 to form a drill slip supporting end 28 and a counterweight end 29. As shown in Fig. 1 of the drawing, the walking beam is formed with a pair of complementary bars 30 which are spaced from each other and extend along opposite sides of the column 14. The portions of the bars constituting the counterweight end 29 of the walking beam are here shown as being parallel and the portions of the bars forming the slip supporting portion of the walking beam 27 are shown as being spread apart for a purpose to be hereinafter described. The bars are disposed with their major width edgewise and vertical and are secured together by transverse brace members 31 and web plates 32 and 33. The portions of the bars which form the end of the counterweight length of the walking beam are enlarged to produce a circular section 34 which agrees in diameter with a plurality of counterweight discs 35. These counterweights are interposed between the bars 30 and are mounted upon a counterweight bolt 36 which passes through bores 37 disposed concentrically of the portions 34 of the bars 30. It is obvious that a desired number of the discs 35 are provided to counterweight the load supported upon the slip supporting length 28 of the walking beam.

Articulately connected with the free end of the portion 28 of the walking beam 27 is a slip supporting unit 38. This unit comprises an outer annular frame member 39, an inner annular slip supporting ring 40 and a plurality of slips 41. The members 39 and 40 do not describe a complete circle but are formed with throats 42 and 75 site tapered faces 75 and 76 which receive the

43 which are of a width sufficient to accommodate a drill pipe 44 when the throats are in register. The annular frame member 39 is provided with a pair of arms 45 and 46 which are spaced equidistant upon opposite sides of the longitudinal center of the walking beam 27. The longitudinal center line of the walking beam intersects the vertical center of the slip supporting unit 38. The arms 45 and 46 are formed at their outer ends with transverse bores 47 and 48 through which trunnion pins 49 and 50 extend. The outer ends of the pins extend into bores 51 and 52 formed transversely of the ends of the bars 30 of the walking beam 27. The pins 49 and 50 thus provide trunnions upon the axis of which the slip supporting unit 38 may swing vertically. It is intended to maintain the slip supporting unit 38 horizontal at all points in the vertical swinging movement of the walking beam 27. This is accomplished automatically by equalizing links 53 and 54. These links are pivoted at one end upon pivot bolts 55 and 56 which extend through the wall of the column 14 at diametrically opposite sides thereof and in the central vertical plane of the column. The axis of the bolts 55 and 56 is spaced from the axis of the king pin 24 and is therebeneath. The opposite ends of the equalizing links 53 and 54 are formed with transverse aligned bores 57 and 58. These receive a pivot pin 59 which extends through transverse bores 60 and 61 of lugs 62 and 63. The lugs are spaced parallel to each other and extend from the side of the annular frame member 39 so that the horizontal axis of the pivot pin 59 will be below and in the same vertical plane as the horizontal axis of the trunnion pins 49 and 50. These axes are spaced apart vertically the same distance as the spacing between the axes of the king pin 24 and the bolts 55 and 56. It will thus be seen that by this arrangement the arm 28 of the walking beam 27 and the equalizing links 53 and 54 will have the effect of a parallelogram and will insure that the slip supporting unit 38 will be maintained in horizontal alignment at all times. The annular frame member 39 is formed with an outer ring-shaped portion 64 which has an overhanging flange 65 at its upper edge. In order to reinforce the frame member 39 a vertically extending rib 66 is cast integral with the flange and circumscribes the opening defined by the frame member. As shown in Fig. 2 of the drawings the rib progressively increases in height from the outer edge of the throat 42 to the arm 45 and then continues between the arms 45 and 46 to form an arcuate reinforcing rib which ties the arms and the overhanging portion of the ring 64 together. Disposed in circumferentially spaced relation to each other around the ring portion 64 of the annular frame member 39 are transverse bores 67 which receive cap screws 68. These cap screws extend into a threaded central bore of cylindrical rollers 69. The outer ends of the rollers 69 are formed with a frustoconical portion 70 and the inner faces of the rollers 69 are formed with a boss 71 which fits within a counterbore 72 in the inner face of the ring portion 64 of the frame.

The rollers 69 are provided to give bearing support to the annular slip ring 40. As shown in Fig. 3 of the drawing, the slip ring 40 has a circumscribing channel in its outer face which provides spaced parallel bearing surfaces 73 and 74 agreeing substantially with the diameter of the rollers 69. The bottom of the channel has opposite tapered faces 75 and 76 which receive the

inclined faces of the frustoconical portion 70 of the rollers. It will thus be seen that the annular slip ring 40 will be supported to rotate around the central vertical axis of the slip supporting unit and will be directly supported by the rollers 69. It will be further noted that due to the formation of the rollers and the contour of the channel into which they extend an anti-friction bearing is provided for the slip ring 40 and means are also provided to prevent lateral movement of the ring 40 with relation to the annular frame member 39. The annular slip ring is designed to provide a direct support for the drill slips 41. These slips are of conventional design having arcuate wickered faces 71 to engage the pipe 44 and arcuate tapered faces 78 to engage the tapered seat 79 of a slip bowl 80. The bowl 80 is mounted within the turntable 80' of an oil well drill rig. The slips are suspended from the annular slip ring 40 by links 81 which are fastened to lugs 82 on the slip ring by bolts 83. The lower ends of the links are fastened to the slips 41 by bolts 84 which pass through the lower ends of the links. In the drawing three slips 41 are shown. It is to be understood that for different sized pipes 44 the annular slip supporting ring 40 may be designed to carry different numbers of slips 41 as required.

To provide for effective guiding of the inner slip carrying ring 40 for only rotary movement, I find it highly important that the outer ring be adapted to guide the inner ring for its rotary movement at at least five different locations spaced angularly about the rings. More specifically, there must be provided means for both supporting the inner ring and retaining it against lateral movement at these five locations. Consequently, it is critically important in the illustrated form of the invention that the number of rollers 69 be at least five, as shown. As will be appreciated, even when one of the rollers is received within the open throat of the inner ring and is thus temporarily inactive, the ring is still adequately supported and guided by engagement with the other rollers at four different locations spaced about more than 180°.

One of the advantages of the present invention is that the entire automatic slip structure may be placed at a proper position upon the derrick floor, after which the column 14 and the walking beam 27 may be rotated around the vertical axis of the standard 11 to swing the slip supporting unit 38 into or away from an embracing relation with the pipe 44. In order to accomplish this conveniently the throats 42 and 43 of the annular frame member 39 and the slip ring 40, when in register with each other, are disposed with their center lines substantially coincident with the arc described by the vertical axis of the slip supporting unit 38 as it swings around the vertical axis of the standard 11. Thus, the walking beam may swing horizontally to place the slip support 38 in an embracing position with relation to the pipe or to swing it away therefrom without making it necessary to move the entire automatic slip unit with relation to the derrick floor.

The walking beam may be oscillated by connecting power applying means to lugs 85 which are secured to a cross-brace 86 disposed between the bars 30 of the walking beam and in the counterweight length 29. Means, such as a fluid cylinder may be connected to the lugs 85 if desired. However, in the present instance a thrust link 87 is provided. This link connects to the

lugs by a pivot bolt 88 and extends downwardly to connect to a lever arm 89 by a pivot bolt 90. The lever arm 89 is fixed to a fulcrum shaft 91. This shaft extends horizontally and is rotatably supported in a bracket 92 carried upon the column 14 near its lower end. Secured to the fulcrum shaft 91 is a hand lever 93 by which the shaft 91 may be rotated. As shown in Fig. 2 of the drawings the hand lever 93 and the thrust link 87 are in position to lower the slip supporting unit 38 toward the rotary table 80'. Attention is directed to the fact that the axis of the fulcrum shaft 91 is spaced sufficiently high above the base plate 10 to permit the free end of the lever arm 89 to swing to a position beyond dead-center when the hand lever 93 is moved in the direction of the arrow a, as indicated in Fig. 2, at which time the walking beam will be oscillated to lift the slip supporting unit from the position shown in Fig. 2. It is also to be pointed out that the axis of the fulcrum shaft 91 is spaced horizontally from the side of the column 14 a sufficient distance to allow the pivot bolt 90 to pass beneath the shaft 91 and the thrust link 87 to pass across dead-center of the shaft 91 so that the walking beam will be locked automatically with the slip supporting unit 38 in its elevated position.

In operation of the present invention the base structure comprising the base plate 10 and the standard 11 are permanently assembled together as shown in the drawings and may be positioned at a desired point with relation to the rotary table 80' of an oil well derrick rig. When it is desired to utilize slips in well drilling operations the entire unit comprising the column 14, the walking beam 27 and the slip supporting unit 38 may be lifted and placed over the upper end of the standard 11. Of course it is to be understood that if desired the entire structure may be assembled and placed on the derrick floor as a unit. There are times however when it would be convenient to remove the walking beam and slip supporting structure so that the derrick floor would not be so crowded, in which event the column 14 may be lifted by the bail 23 and carried from place to place. When the column 14 is placed in position over the standard 11 it is preferable that the lever 93 shall be in its dotted line position, as shown in Fig. 2. This places the pivot bolt 90 beyond dead-center at the bottom of the column 14 and thus insures that the walking beam 27 will be supported in its uppermost position. When placing the column 14 in position over the standard 11 so that the standard 11 may protrude up into the column it is desirable to rotate the walking beam 27 at substantially right angles to the vertical plane it will normally occupy when the slips are being used. At such a time the latch dog 20 will extend through the opening 21 in the column 14 and will rest against the outer surface of the standard 11. The dog will be yieldably held in this position by the spring 19. At this time it will also be obvious that the throat 43 of the annular slip ring 40 will be moved to register with the throat 42 of the annular frame member 39. The slips 41 will then be hanging vertically from the links 81. When it is desired to use the slips the portion 28 of the walking beam is rotated in the direction of the arrow b in Fig. 1, and if the base plate 10 and standard 11 have been properly set this swinging movement will cause the slip unit to swing around so that the drill pipe 44 will pass through the throats 42 and 43 of the members

39 and 40 respectively. When the drill pipe has assumed a position substantially at the center of the slip supporting unit 38 the annular slip supporting ring 40 may be rotated upon its vertical axis. During this rotation the ring 40 will ride on the rollers 68. Thus the rotation of the slip supporting ring may be easily accomplished. When the slip supporting ring 40 has been rotated on its vertical axis until the throats 42 and 43 are out of register completely the pipe 44 will be encircled by the drill slip unit 38. The power operating levers 93 may then be swung in a direction counter to that indicated by the arrow *a* in Fig. 2. This will lift the counterweight end 32 of the walking beam and will lower the slip supporting unit so that the slips 41 will find their way downwardly along the tapered faces 78 of the bowl and will come to rest with their inner wickered faces 77 impinging against the circumference of the drill pipe 44. When in this position the slips will support the pipe 44 and allow such operations to take place as are desired. After the slips have served their useful purpose the lever 93 may again be moved in the direction of the arrow *a* in Fig. 2. This will cause the link 31 to swing the counterweight end 32 of the walking beam 27 downwardly and to lift the slip supporting unit 38 free of the rotary table 80 so that the slips 41 may swing free of the drill pipe. Attention is directed to the fact that the bolts 83 from which the slip links 81 are suspended are spaced a greater radial distance from the vertical axis of the slip supporting unit 38 than the distance assumed by the bolts 84 at the lower ends of the links when the slips are in their set positions. This insures that as the slip unit is lifted there will be a tendency for the links to act automatically and pull the slips away from the pipe 44. When the links 31 and the slips are lifted clear of the bowl there will be considerable space between the circumference of the drill string and the inner wickered faces 77 of the slips 40. This space may provide sufficient clearance to permit a drill joint to pass downwardly through the slip supporting unit 38 without requiring that the throats 42 and 43 shall register and that the walking beam shall be rotated on its vertical axis in a direction counter to that indicated by the arrow *b* in Fig. 1.

As has been previously explained, power means may be used to raise and lower the walking beam 27, such for example as by the use of an hydraulic cylinder or other equivalent means.

It will thus be seen that the automatic drill slip unit here disclosed provides simple mechanical means whereby a plurality of drill slips may be mechanically handled in a manner to be placed in position within a slip bowl and around a pipe simultaneously, as well as in a manner to be easily and quickly removed therefrom, the structure being counterbalanced and provided with mechanical moving means so that the entire operation of using the slips may be easily accomplished by one man. It will also be seen that by the structure here disclosed the drill slip supporting unit may be easily swung toward and away from an embracing position with relation to the drill pipe, and may be easily lifted with the associated mechanism so that it can be removed from an obstructing position on the derrick floor.

While I have shown the preferred form of my invention as now known to me, it will be understood that various changes may be made in combination, construction and arrangement of parts

by those skilled in the art, without departing from the spirit of my invention as claimed.

Having thus described my invention, what I claim and desire to secure by Letters Patent is:

1. In an automatic drill slip unit, an outer arcuate member having a gap in a side thereof to admit a drill pipe therethrough, an inner arcuate drill slip support member adapted to be inserted in said outer arcuate member, a plurality of rollers removably mounted on one of said arcuate members and having rolling rotatable support relatively to the inner arcuate member for concentric relative rotative movement between said arcuate members, the inner arcuate member having a gap therein adapted to register with the gap in the outer member to pass a drill pipe therethrough, the inner arcuate member being adapted to be moved rotatably relatively to the outer arcuate member to close the gap and retain a drill pipe therein, and a plurality of tapered slips suspended from the inner arcuate member when elevated above a rotary table with the lower edges of said slips disposed radially inwardly of the upper edge of the tapered seat when so elevated to guide the slips into the seat on lowering the unit from an elevated position over the seat.

2. In a drill slip unit, a support member adapted to extend partially about a vertically extending drill pipe and having an opening at one side through which the pipe may pass upon movement of the member into position about the pipe, a slip carrying member adapted to extend partially about the pipe and mounted by the support member for rotation relative thereto and about the pipe, said slip carrying member having an opening at one side adapted to pass the pipe and movable into registry with said opening in the support member by said rotation of the slip carrying member, bearing means carried by one of said members and engageable with the other member at at least five different locations spaced angularly about said one member to guide the slip carrying member for said relative rotation, a plurality of tapered pipe gripping slip elements, and connecting means movably mounting said slip elements to the slip carrying member in depending relation thereto for reception in a slip bowl positioned beneath the members.

3. In a drill slip unit, a support member adapted to extend partially about a vertically extending drill pipe and having an opening at one side through which the pipe may pass upon movement of the member into position about the pipe, a slip carrying member adapted to extend partially about the pipe and mounted by the support member for rotation relative thereto and about the pipe, said slip carrying member having an opening at one side adapted to pass the pipe and movable into registry with said opening in the support member by said rotation of the slip carrying member, bearing means carried by one of said members and engageable with the other member and giving support to said slip carrying member for said rotation at at least five different locations spaced angularly about said one member, a plurality of tapered pipe gripping slip elements, and connecting means movably mounting said slip elements to the slip carrying member in depending relation thereto for reception in a slip bowl positioned beneath the members, said slip elements and connecting means being formed to provide between a pair of the slip elements while they are mounted to the slip carry-

ing member a gap through which the pipe may pass.

4. In a drill slip unit, a support member adapted to extend partially about a vertically extending drill pipe and having an opening at one side through which the pipe may pass upon movement of the member into position about the pipe, a slip carrying member adapted to extend partially about the pipe and mounted by the support member for rotation relative thereto and about the pipe, said slip carrying member having an opening at one side adapted to pass the pipe and movable into registry with said opening in the support member by said rotation of the slip carrying member, bearing means on one of said members engageable with the other member at at least five different locations spaced angularly about said one member and acting to prevent substantial relative bodily movement of the members transversely of the axis of said rotation, a plurality of tapered pipe gripping slip elements, and connecting means movably mounting said slip elements to the slip carrying member in depending relation thereto for reception in a slip bowl positioned beneath the members, said slip elements and connecting means being formed to provide between a pair of the slip elements while they are mounted to the slip carrying member a gap through which the pipe may pass.

5. In a drill slip unit, a support member adapted to extend partially about a vertically extending drill pipe and having an opening at one side through which the pipe may pass upon movement of the member into position about the pipe, a slip carrying member adapted to extend partially about the pipe and mounted by the support member for rotation relative thereto and about the pipe, said slip carrying member having an opening at one side adapted to pass the pipe and movable into registry with said opening in the support member by said rotation of the slip carrying member, means forming a connection between the members and including at least five rotatable bearing elements engageable with the members at as many locations spaced thereabout and guiding the slip carrying member for said relative rotation, and a plurality of tapered pipe gripping slip elements carried by said slip carrying member.

6. In a drill slip unit, a support member adapted to extend partially about a vertically extending drill pipe and having an opening at one side through which the pipe may pass upon movement of the member into position about the pipe, a slip carrying member adapted to extend partially about the pipe and mounted by the support member for rotation relative thereto and about the pipe, said slip carrying member having an opening at one side adapted to pass the pipe and movable into registry with said opening in the support member by said rotation of the slip carrying member, one of said members having a partial annular bearing surface, at least five rollers rotatably carried by the other member and engageable with said bearing surface to give support to the slip carrying member at at least five different locations spaced angularly about said other member, a plurality of tapered pipe gripping slip elements, and connecting means movably mounting said slip elements to the slip carrying member in depending relation thereto for reception in a slip bowl positioned beneath the members.

7. In a drill slip unit, a rigid generally arcuate support ring adapted to extend partially about

a vertically extending drill pipe and having an opening at one side through which the pipe may pass upon movement of the ring into position about the pipe, a rigid generally arcuate slip carrying ring adapted to extend partially about the drill pipe and mounted at the inside of said support ring for rotation relative thereto about the pipe, said slip carrying ring having an opening at one side adapted to pass the pipe and movable into registry with said opening in the support ring by said rotation of the slip carrying ring, means forming a connection between the rings and including at least five rotatable bearing elements engageable with the rings at as many locations spaced thereabout and guiding the slip carrying ring, for said rotation, the angular extents of said openings in the sides of the rings and the spacing of said rollers being such that in all relative rotative conditions of the rings at least four of the rollers spaced about more than 180° are actively interposed between the rings, a plurality of tapered pipe gripping slip elements, and connecting means movably mounting said slip elements to the slip carrying ring in depending relation thereto for reception in a slip bowl positioned beneath the member.

8. In a drill slip unit, a rigid generally arcuate support ring adapted to extend partially about a vertically extending drill pipe and having an opening at one side through which the pipe may pass upon movement of the ring into position about the pipe, a rigid generally arcuate slip carrying ring adapted to extend partially about the drill pipe and mounted at the inside of said support ring for rotation relative thereto about the pipe, said slip carrying ring having an opening at one side adapted to pass the pipe and movable into registry with said opening in the support ring by said rotation of the slip carrying ring, one of said rings having a partial annular bearing surface having transverse extent both vertically and horizontally, at least five rollers carried by the other member at as many locations spaced angularly thereabout and having surfaces engaging said annular surface to both support the slip carrying ring for said rotation and to prevent substantial relative movement thereof transversely of its axis of rotation, the angular extent of said partial annular bearing surface and the spacing of said rollers being such that in all relative rotative conditions of the rings at least four of the rollers spaced about more than 180° are effectively interposed between the rings, a plurality of tapered pipe gripping slip elements, and connecting means movably mounting said slip elements to the slip carrying ring in depending relation thereto for reception in a slip bowl positioned beneath the rings.

9. In a drill slip unit, a rigid arcuate support ring adapted to extend horizontally partially about a vertically extending drill pipe and having an opening at one side through which the pipe may pass upon movement of the ring into position about the pipe, a rigid arcuate slip carrying ring adapted to extend horizontally partially about said drill pipe and mounted at the inside of said support ring for rotation relative thereto about the pipe, said slip carrying ring having an opening at one side adapted to pass the pipe and movable into registry with said opening in the support ring by said rotation of the slip carrying ring, said slip carrying ring having an arcuate recess in its outer surface facing the support ring, and having upper and lower 75 roller engaging walls, said walls having outer

11

horizontal portions and inner angularly converging portions, at least five rollers mounted to said support ring at as many locations evenly spaced angularly thereabout, each of said rollers having an outer cylindrical portion engageable with said horizontal portions of said recess walls and having an inner frustoconical portion engageable with said angular portions of the walls, a plurality of tapered pipe gripping slip elements, and connecting means movably mounting said slip elements to the slip carrying ring in depending relation thereto for reception in a slip bowl positioned beneath the member, said slip elements and connecting means being formed to provide between a pair of the slip elements while they are mounted to the slip carrying ring a gap through which the pipe may pass.

10. A drill slip unit comprising a first member adapted to be positioned above a rotary table and to extend about a drill pipe extending vertically through the table, a support to be mounted at a side of the table, means mounting said member to the support for movement between an active position above the center of the table and a retracted position offset to the side thereof, said member having an opening at one side adapted to pass the pipe upon said movement of the member between said positions, a second member adapted to extend partially about the pipe and

12

mounted by said first member for rotation relative thereto and about the pipe, said second member having an opening at one side adapted to pass the pipe and movable into registry with said opening in the first member upon said rotation thereof, bearing means carried by one of said members and engageable with the other member at at least five different locations spaced angularly about one member to guide the second member for said relative rotation, a plurality of tapered pipe gripping slip elements, and connecting means movably mounting said slip elements to the second member in depending relation thereto for reception in a slip bowl positioned beneath the members.
